CLOSURE ARRANGEMENT

Kenneth H. MacKay, Ocala, Fla.

Continuation of application Serial No. 125,337,
February 11, 1937. This application February
2, 1938, Serial No. 188,343

15 Claims. (Cl. 121—73)

This invention relates to closure arrangements, and particularly to such arrangements whereby an effective seal may be provided between relatively moving mechanical parts. Such devices 5 may be employed in a wide variety of environments, one example of which is a rotary motor or compressor of the type disclosed in my copending application Serial No. 220,689, filed July 22, 1938. Such a machine is provided with slide 10 valves which may be constructed to operate in the manner taught by this invention. Such a motor or compressor is also provided with cam operated abutments movable into and out of the path of rotary vanes to cooperate therewith in 15 providing expansible or contractible fluid-containing chambers, and these abutments may also be constructed and arranged to operate in the manner taught by the present invention.

In general, however, the principles of this invention are applicable to movable closures such as valves, pistons, plungers, or the like, where it is desired to afford an effective fluid-tight seal between the surface of the closure and the surface of a cooperating member.

To permit these desirable results, the closure assembly may afford a fluid-containing chamber with a wall portion thereof provided by the movable closure member, suitable hydraulic means being provided to force fluid under pressure into 30 the chamber thereby to cause the movable wall portion firmly to be pressed against a cooperating guide surface, thereby affording an effective fluid-tight seal for the valve, plunger, movable abutment or the like. Such a hydraulic arrangement 35 may also be arranged to cause the actuation of the closure. This actuation may be effected periodically against the action of a suitable return spring or springs. If desired, the fluid which causes movement of the wall portion 40 of the closure may also be circulated so that the closure is cooled by the fluid. In certain cases, it may be desirable to have the wall portion move relative to the closure under the control of fluid in order to ensure a firm engagement of parts, 45 as the firm engagement of the head portion of an abutment and a complementary recess of the general type disclosed in my above-identified application or, if preferred, such a head portion or the like may be given an accelerated movement 50 compared to the remainder of the abutment member, so that the effect is realized, which would be obtained if a more steeply shaped cam were provided for actuating the abutment member.

In one typical embodiment of the invention, a

hollow slide valve may be provided which is hydraulically actuated by fluid which is also effective in tending to press the thin walls of the slide valve firmly against the channel in which the valve is slidable thereby to afford an effective seal. Such an arrangement may also be provided so that oil is circulated through the slide valve between each period of operation thereby effectively to cool the valve. Another arrangement involves the provision of thin-walled extensible chambers on the heads of abutment members which are pressed firmly against the channels in which the abutments slide, while the heads of the abutment members may be movable relative to the remainder thereof so that an unusually firm and effective seal is afforded. A somewhat similar arrangement may be provided to cause the acceleration of the head of the member relative to the body portion thereof, thus giving a degree of acceleration to the head of the abutment member which would be afforded were a relatively steep cam employed to actuate the abutment member.

In the accompanying drawings:

Fig. 1 is a vertical sectional view of a slide valve assembly showing hydraulic means for actuating a valve and for pressing the surface of the valve firmly against its channel when the valve is actuated and for cooling the valve;

Fig. 2 is a vertical section of part of an engine cylinder head structure having incorporated therein valve actuating means embodying my invention. In this showing the cylinder head structure is that of a conventional reciprocating internal combustion engine;

Fig. 3 is a vertical sectional view of an abutment assembly such as is provided in my above-identified copending application, the assembly, however, being modified in accordance with the principles of the present invention;

Fig. 4 is a section indicated by line 4—4 of Fig. 3;

Fig. 5 is a view similar to Fig. 3, but showing certain parts of the assembly in a somewhat different relative position;

Fig. 6 is an enlarged sectional detail of a portion of the assembly shown in Figs. 3 and 5;

Fig. 7 is an isometric view of a retaining member provided on the abutment shown in Figs. 3 and 5;

Fig. 8 is a view similar to Fig. 3, but showing an optional arrangement of an abutment assembly with means provided to accelerate the abutment head at the end of its path; and

Fig. 9 is a view of an optional arrangement of an abutment assembly.

In the accompanying drawings, certain closure arrangements are illustrated which may be employed in a motor or compressor of the character shown in my above-identified application, but it is to be understood that this disclosure is but an example of various closures which may operate in accordance with the principles of this invention to provide the same general advantages.

Fig. 1 shows a portion of an annular casing 1 on which a slide valve 2 is mounted to reciprocate in a channel 3 provided by an extension 4 of the annular casing. This valve is slidable to cover 15 or uncover suitable ports 5 through which fluid, such as a gaseous charge, may pass. Compression springs 7 are provided at each side of the port yieldably to urge the valve toward its open position, and when these springs are fully compressed, they limit the movement of the valve away from its open position. When the valve has moved to its closed position, it extends across the ports 5 so that the movement of the gaseous charge through the ports is prevented.

As shown, the valve 2 may be in the form of a box-like member of relatively thin metal having an open end which is slidably received in suitable recesses defined by a sealing member 10 which fits within the end of the box-like valve member. The sealing member 10 is provided with an open end communicating with a passage 12 that in turn communicates with a plunger chamber 13 in the annular casing 1. A plunger 14 is slidably mounted in this chamber, being provided 35 with an end portion 15 which affords a follower for an actuating cam 16, the movement of the plunger 14 by the cam 16 being opposed by a compression spring 17 which is disposed eccentrically about a spindle 18 extending from the plunger into the chamber 13 and having an end portion 19 slidable in a collar 23 at the end of the chamber.

It is to be understood that when the cam 16 actuates the plunger 14, hydraulic fluid is forced 45 from the chamber 13 through the passage 12 into the interior of the box-like guide 10 and the hollow valve 2, thus causing the valve to slide outwardly to cover the ports 5 against the action of the springs 7. Furthermore, since the slide 50 valve 2 is formed of thin metal, the hydraulic pressure thus imposed tends to press the surfaces of the valve more firmly against the walls of the channel 3 in which the valve is slidable, thereby assuring an effective fluid-tight seal when the 55 slide valve closes the ports 5.

A second radially disposed plunger 30 is slidably mounted in the casing 1, being movable by a cam 31 against the action of a compression spring 32. This plunger is provided with a portion 33 of reduced diameter which, when the plunger moves outwardly, registers with a passage 29 communicating with the open end of the guide 10 and the interior of the valve 2 and with an outlet duct 34 from which oil may drain to a 60 suitable sump (not shown).

The plunger 30 is also provided with a second annular groove 37 which communicates with an inlet duct 38 through which oil is supplied under pressure, as, for example, from a suitable conventional oil pump or other means, not shown, which also may supply oil under pressure for lubricating the motor or the like. The groove 37 also communicates with a supply passage 40 through which oil received from the duct 37 may 65 pass to the chamber 13 and thence to the in-

terior of the guide 10 and the slide valve 2, filling the passages 12 and 29 which communicate therewith.

In order to prevent the passage of the incoming oil directly from chamber 13 to the outlet 5 duct 34, a suitable deflector 43 may project radially from the casing, this deflector having a lower upwardly inclined surface to prevent the pocketing of air. In order to permit surplus oil to be emitted from the chamber and to permit air to pass out from the chamber, the spindle 18 is provided with an orifice 50 at the top of the chamber which bleeds the air from the chamber together with excess oil.

In the operation of a valve of this character, 15 it is to be understood that the cams 16 and 31 are fixed to the main shaft of the motor or compressor and that these cams respectively engage the plungers 14 and 30 in succession. When the cam 31 engages the plunger 30, the latter is 20 moved radially outward so that the groove 37 first causes the passages 38 and 40 to communicate with each other so that there is a tendency for the pressure from the oil supply line from the pump (not shown) to force oil through the passage 40 into the chamber 13. Since, however, this chamber may be normally full of oil, there is little tendency toward movement of the oil through these passages until the continued movement of the plunger 30 causes the passage 29 to 25 communicate with the outlet 34. Thereupon the oil within the hollow valve 2 and the guide 10 may drain through the passage 34 to the sump. This oil may be relatively warm and is replaced by cooler oil entering the chamber through passage 40.

The incoming oil is prevented by the deflector 43 from passing directly to the outlet 34 and thence to the sump, so that circulation of oil takes place in the hollow valve 2 and the latter is effectively cooled by the incoming oil, which replaces a substantial portion of the oil previously contained in the chamber. Thereupon as the plunger 30 returns to its normal position under the influence of spring 32, the passage to the outlet 34 is first closed, while oil continues to enter through the duct 40 so that substantial filling of the chamber is assured. Since, however, the orifice 50 is at the upper part of the chamber, collected air will pass out of this orifice, while surplus oil may also pass out of the chamber in this manner.

After the plunger 30 has thus been actuated, the valve 2, which is in its open position, is filled with relatively cool oil and the movement of the cam-shaft continues until the cam 16 engages the plunger 14, whereupon the orifice 50 moves into the collar 23 so that the emission of fluid through the orifice is prevented as the plunger continues to move inwardly, forcing the oil under pressure into the valve chamber and causing the latter to move radially outwardly against the action of springs 7. As this occurs and particularly at the end of such movement, the pressure within the hollow slide valve 2 is materially increased so that the surfaces thereof, and particularly the flat side surfaces, are pressed more firmly against the sides of the channel in which the valve 2 slides.

The valve 2 is thus held in its closed position until the cam 16 permits the spring 17 to return the plunger 14 to its normal position. The parts then remain in this position until the plunger 30 is again actuated to permit warm oil to be released from the valve chamber and cooler oil to replace the same.

It is evident that this arrangement may be employed to permit the hydraulic actuation of a closure, such as a slide valve, to permit the concomitant cooling of the valve, and to cause the distention of the thin-walled valve member so that its outer surfaces are more firmly pressed against the cooperating surfaces of the guide channel.

Fig. 3 illustrates an abutment member, designated generally by numeral 60, which is actuatable by a cam 61 engaging a follower 62 secured to a spindle 63. A coil compression spring 64 may be arranged to press the follower 62 against the cam and to return the abutment member to its normal position after the cam has passed out of engagement with the follower. Such an abutment member, as shown in my above-identified application, may be movable into a channel 65 to cooperate with blades rotatable in that channel in defining fluid-containing chambers. Preferably, as shown, such an abutment member is provided with a beveled surface defining one side of a bluntly pointed end portion which is engageable in a complementary recess 67 on the inner wall of the channel 65.

In accordance with the present invention, the abutment member may comprise an outer plate 68 which is fixed to the spindle 63 and an inner head 66 which is slightly movable relative to the spindle and the plate 68. For this purpose an extension 63a of the spindle, which is of reduced diameter, may have a sliding engagement with a suitable bore in the head portion 66, while a light compression spring 70 is disposed between a shoulder on the spindle 63 and a shoulder on the head portion tending to urge the head portion away from the plate 68. This relative movement, however, is limited by a diametric pin 71 extending through the spindle 63 so that only limited movement of the parts can take place.

In accordance with this invention, the abutment member 60 is slidable in a suitable channel 74 disposed outwardly of the channel 65, and when the abutment member is in its outermost position, the space or chamber 75 between the plate 68 and the head 66 communicates with an oil supply passage 78 through which oil may be supplied under pressure from a conventional lubricating oil pump, not shown. Accordingly this chamber is filled with oil when the abutment 60 is retracted. Thereupon, when the cam 61 advances the abutment so that it extends across the channel 65, the oil in the chamber 75 is subjected to pressure and the spring 70 is slightly compressed. Thus the head 66 is firmly pressed against the recess 67 in the inner wall of the channel 65.

Furthermore, the chamber 75 communicates through suitable passages 80 in the head 66 (Fig. 6) with thin-walled chambers or channels 81 which extend along three straight surfaces of the abutment member, so that these channels are filled with the hydraulic fluid. Accordingly, when the pressure is increased due to the movement of the outer plate 68 toward the head 66 and particularly at the end of such movement, the outer walls of channels 81 are distended outwardly. A retaining member 85 of the form shown in Fig. 7 may extend about the outer surfaces of these channels, this member being provided with an inturned flange 86 which extends about the end of the channel at one end of the abutment member and being provided with an outturned flange 87 at the opposite end of the abutment member which slides in a suitable re-

cessed portion of the guiding frame. As shown, the upper part of the retaining member 85 may be provided with relatively deep vertical slits 88 to permit the slight distention of this portion of the retaining member, as the channels 81 are distended under the hydraulic pressure. Accordingly, the outer surface of the retaining member is firmly pressed against the complementary surfaces of the guide passage 74 for the abutment member. Thus an effective fluid-tight seal may be provided between these parts.

When the abutment member moves outwardly, the plate 68 moves slightly away from the head 66 to relieve the hydraulic pressure, whereupon the pin 71 is effective in causing the head to move with the plate 68 and spindle 63 as these parts continue their outward movement. As this movement is terminated, the chamber 75 again communicates with the passage 78 so that any oil which has leaked out of the chamber 75 may be replenished, whereupon the operating cycle may be repeated.

Openings 88 preferably may be provided in the inner ends of the channels 81 to permit slight leakage of fluid from these channels when the fluid is subjected to increased pressure, due to the movement of plate 68 toward head 66. Thus any pocketed air may be vented for the fluid-containing space and oil may be supplied to the wall of channel 78 to aid in lubricating the same.

Referring to Fig. 2 which shows the hydraulic closure of my invention in a reciprocating internal combustion engine: Cylinder head structure 201 is shown having a hollow sliding valve 202 mounted therein and maintained in open position with respect to passage 225 by the compression spring 203, the said cylinder head structure including an upper valve actuator structure 204 chambered to provide a valve actuator chamber 205 to the interior of which the open end of the valve 202 is exposed. This chamber is intended to contain a hydraulic fluid, such as oil, which acts as a means of transmitting motion to the valve 202 from an actuator plunger 206, one end of which plunger is also exposed to the interior of said actuator chamber 205 and the other end is pressed against a cam 207 by a plunger spring 208 so that the said plunger will follow the contour of the said cam.

209 is a fluid manifold preferably supplied with oil under pressure, and 210 is a check valve adapted to open from the said manifold into the actuator chamber 205 when pressure in the manifold 209 exceeds pressure in the actuator chamber to an extent sufficient to overcome the resistance of the check valve spring 211. The check valve is indicated as being housed in a casing 212 having a port 213 communicating with the manifold, and a further port 214 communicating with the actuator chamber to permit the required flow from the manifold to the actuator chamber when the check valve is open. This casing is held in position on suitably provided seats by the plug 215 in the top of the actuator structure.

The actuator structure 204 is also shown as housing a further plunger 216 which forms a relief valve as will be explained, this plunger having its lower end also bearing on the cam 207, by reason of the action of the relief valve spring 217 confined between the said plunger and a plug 218 in the upper end of the said actuator structure 204, the said plunger 216 being so arranged radially of the cam that its operation alternates with that of the plunger 206.

The plunger 216 is tubular and has an outlet passage at its lower end and an inlet passage 220 towards its upper end, which inlet passage opens from an annular groove 221 in the said 5 plunger 216 adapted to register with a relief port 222 of the actuator chamber 205 when the said plunger 216 is raised to a sufficient extent by the lobe of the cam 207. This relief port 222 opens from a high point or region of air accumulation in the actuator chamber 205.

Arranged within the tubular plunger 216 is a spring pressed check valve 223 permitting outward or downward flow only through the said plunger.

15 As previously explained, rotation of the cam 207 effects intermittent lifting of the plunger 206 and the consequent operation of the valve 202, and during such time as the valve 202 is closed and the plunger 206 in a position other than dwelling 20 on the base circle of the cam, fluid in the actuator chamber 205 is subjected to considerable pressure so that there is no tendency of the check valve 210 to open. During this pressure period the plunger 216 dwells on the base circle of the cam so that 25 the annular groove 221 thereof and the relief port 222 of the actuator chamber do not register, the hydraulic fluid, therefore, being effectively confined in the actuator chamber.

After the lobe of the cam passes beyond the 30 actuator plunger 206 in whichever direction the said cam may rotate, it eventually raises the plunger 216 until the annular groove 221 thereof coincides with the relief port 222 of the actuator chamber, but at this time it will be understood 35 the plunger 206 again dwells on the base circle of the cam, and the valve 202 is open so that there is then no pressure exerted on the fluid in the actuator chamber. As a consequence, slight pressure of fluid in the manifold 203 will lift the 40 check valve 210 and result in flow taking place through the actuator chamber and therefrom by way of the relief port 222 through the hollow interior of the plunger 216 and the outlet passage 219. The check valve 223 offers but little resistance 45 to this flow which is easily overcome.

The said flow of oil through the actuator chamber during the period of valve inaction is effective 50 both to scavenge air from the said chamber and to ensure a replenishing of oil therein to compensate for any loss by leakage or otherwise, whereby a complete filling of the chamber with oil prior to the ensuing valve actuating movement of the plunger 206 is ensured as required to ensure proper translation of plunger movement into 55 valve movement.

The valve 202 may be of rectangular box-like form having an open end slidably fitting within the guide 224, it being evident that when the valve 202 is moved to its closed position against the 60 action of spring 203, the thin walls of the hollow valve are distended, thereby to afford an effective fluid-tight seal. While the slide valves illustrated in Figs. 1 and 2 are of rectangular box-like form, it is evident that the shapes of these valves may be 65 varied as desired. Thus, for example, such valves might be provided with curved or arcuate cross sections, or they might have cylindrical cross sections.

Fig. 8 illustrates an abutment assembly with the 70 parts arranged similarly to those shown in Figs. 3 to 7, such parts being designated by similar reference numerals. However, in accordance with this embodiment of the invention, a slot 90 communicates with the chamber 75 and an oil duct 78^a is arranged to supply oil through the passage 90 to

the chamber 75. This duct 78^a preferably communicates with a small plunger pump, designated in general by numeral 95, which may receive oil from the oil pressure line of the motor or compressor. This pump 95 may be located at any convenient point remote from the abutment assembly, being provided with the piston 96 which is provided with a rod 97 having a follower 98 engaging an operating cam 99. A spring 100 presses the piston 96 toward the cam 99 so that the follower 10 is held in engagement with the cam. When the piston moves downwardly, oil is admitted to the chamber of the pump through the passage 108. A suitable check valve 104 in the passage 108 is provided to prevent the movement of oil from this chamber when the piston 96 moves toward the cylinder head under the action of cam 99. As this occurs a pressure impulse is imparted to the oil contained in the duct 78^a, the groove 90, and the chamber 75. A check valve 78^b permits the flow of 15 oil through the duct 78^a to the groove 90 and the chamber 75 as the piston 96 moves upwardly to provide a pressure impulse. The parts are so synchronized that this impulse is provided just as the abutment head approaches the end of its path, 20 so that a movement of the abutment head inwardly toward the channel 65 relative to the spindle 63 and the plate 68 is provided. Accordingly, while the last-named parts are moving inwardly 25 toward channel 65, the movement of the head is 30 accelerated and the latter receives a total movement similar to that which would be provided if the actuating cam were provided with a steeper rise. Thus the head may move more rapidly 35 across the channel 65, while at the same time this head may be provided with the thin-walled sealing channels 81 which are distended in the manner already described with reference to Figs. 2 to 7 inclusive. This movement of the head relative 40 to the remainder of the abutment assembly is 45 yieldably opposed by a compression spring 170 disposed in a recess 166 between the enlarged portion 163^a of the spindle 63, and a shoulder 50 provided by the abutment head. Accordingly, when the pressure within the chamber 75 is released, the head is moved by the spring 170 55 toward the plate 68.

The pressure within the chamber 75 may be released by means of the piston 96, the side wall portion of which is provided with a recess 133 affording communication between a duct 134 extending from the chamber 75 and a relief duct 134'. Thus, as the cam 99 passes out of engagement with the follower 98, the spring 100 moves the piston 96 downwardly so that the pressure in 55 chamber 75 is relieved and the spring 170 may be effective in moving the abutment head toward the plate 68, this action tending to squeeze some of the oil from the chamber 75. Obviously, this relative movement of the parts of the abutment assembly may occur as the latter is starting its outward movement away from the recess 67. Thus a movement is afforded for the abutment head like that which might be provided were the cam to have a more steeply inclined surface 60 65 engaging the follower as the abutment moves outwardly.

Fig. 9 shows an optional arrangement of an abutment of the general character illustrated in Fig. 8. Such an abutment may be actuated by a 70 cam 61, which engages a follower 162 at the end of a spindle 163. As shown, a compression spring 164 tends to move the abutment out of the channel 165 and to hold the follower 62 against the cam 61. The abutment includes a plate 168 75

fixed to the spindle 163 and a head portion 160 movable on the end of the spindle. For this purpose, the end of the spindle is provided with an enlarged portion 163a which engages the end of a compression spring 168 in a recessed portion 170 of the head. The spring 168 tends to urge the head 160 toward the plate 168, the part 163a acting as a stop to limit this movement. When the follower is engaged by the cam 61, the abutment is moved to the position indicated in dot and dash lines in Fig. 9, so that the bluntly pointed end of the abutment is engaged in the recess 167 in the wall of channel 165. This abutment may be provided with any suitable chambers having distensible wall portions. As shown, a narrow channel 180 is provided in the head 160, this channel having an outer wall provided by a thin plate 185 integral with the body portion of the head.

The space between the plate 168 and the head 160 affords a fluid containing chamber which communicates through a passage 178 with a chamber in which a plunger 196 is slidably mounted. The plunger 196 is provided with a follower 198, which is engaged by the cam 61 directly after the cam engages the follower 162. As this occurs, the plunger moves inwardly, compressing the spring 197, and causing oil which is supplied through a duct 103 from any suitable source of supply to be forced outwardly through the check valve 195 and the passage 178 into the space between the plate 168 and the abutment head 160. Thus at the end of the inward path of the abutment assembly, an accelerated motion is imparted to the head 160, due to the pressure impulse imposed by the plunger 196. Preferably, as shown, the inlet duct 103 for the plunger chamber may be provided with a check valve 104.

As the cam 61 continues its movement, it engages a third follower 122 mounted on the end of a plunger 121 having an annular groove 233. This action occurs as the cam passes out of engagement with the follower 162 and the spring 164 tends to return the abutment assembly to its outermost position shown in full lines. As the plunger 121 is moved inwardly, the annular groove 233 permits the passage 234 to communicate with the relief duct 234', thus permitting the oil pressure between the members 168 and 160 to be released, as the spring 178 is effective in moving the abutment head 160 toward the plate 168.

It is thus evident that the arrangement shown in Fig. 9 affords an assembly whereby the abutment, the abutment head, and a relief valve, may be actuated by a single cam, so that as the abutment moves inwardly, the head 160 has an accelerated motion such as would be afforded were the abutment being actuated by a cam having a more abrupt rise, and so that as the abutment moves outwardly, the spring 166 is effective in giving the head 160 an accelerated motion in an outward direction.

It is evident that the present invention provides closure members which may include movable wall portions that are pressed into firm engagement with the surfaces of cooperating guide wall portions to afford a fluid-tight seal and that such an action may take place concomitantly with the hydraulic actuation of the closures, if desired, or that such action may take place while a portion of the closure is being accelerated or decelerated relative to the remainder thereof, and also that an arrangement of this character may be associated with suitable means period-

ically to replace the hydraulic fluid to cool the closure.

While devices of this character have been illustrated and are in fact particularly applicable to a motor or a compressor of the type disclosed in my above-identified application, it is to be understood that the principles of the invention may be employed generally with slide valves, plungers and similar forms of closures.

It should be understood that the present disclosure is for the purpose of illustration only and that this invention includes all modifications and equivalents which fall within the scope of the appended claims.

This application is a continuation of applicant's earlier-filed application, Serial No. 125,337, filed February 11, 1937.

I claim:

1. A closure assembly comprising relatively movable members, said assembly affording a fluid-containing chamber with a wall portion thereof provided by one of said members and movable relative to the opposite wall of the chamber, said wall portion providing an outer surface juxtaposed to a cooperating surface of the other member, and hydraulic means effective to cause the relative movement of said members in response to hydraulic pressure and concomitantly to subject the fluid in said chamber to increased pressure to cause movement of said wall portion in the direction of the relative movement of said members to cause said wall portion to have an accelerated rate of movement relative to the other member.

2. A slide valve assembly comprising a hollow fluid-containing valve, a guide structure in which said valve is movable, said structure providing a guide extending into and interfitting with the end of said hollow valve, and means for actuating said valve to slide the same along a path defined by said structure and for distending the valve at the end of its path.

3. An abutment assembly comprising a spindle, a plate fixed to the spindle, a head having a slight movement relative to the spindle, a spring tending to move the head toward the plate, means for actuating and guiding said assembly, and hydraulic means for causing the movement of the head away from the plate as the assembly is being actuated.

4. An abutment assembly comprising a spindle, a plate fixed to the spindle, a head having a slight movement relative to the spindle, a spring tending to move the head toward the plate, means for actuating and guiding said assembly, and hydraulic means for causing the movement of the head away from the plate as the assembly is being actuated, said head including a chamber which is hydraulically distended as the head is moved away from the plate.

5. Mechanism of the class described, comprising a movable assembly, guiding structure for said assembly defining the path of the same, actuating means directing the assembly along said path, said assembly comprising a body portion and a head portion movable relative thereto, said assembly providing a fluid-containing chamber between said portions, and means to subject the fluid in said chamber to a pressure impulse to cause the head portion to accelerate relative to the body portion as said assembly is moved along its path by the actuating means.

6. Mechanism of the class described, comprising a slide valve, a guide channel in which said valve is slidable, said valve affording a hollow

thin-walled chamber and having walls distortable under hydraulic pressure, and hydraulic means for periodically sliding the valve in its channel and hydraulically distending the walls 5 of the chamber when said sliding is completed.

7. Mechanism of the class described, comprising a slide valve, a guide channel in which said valve is slideable, said valve affording a hollow thin-walled chamber and having walls distortable 10 under hydraulic pressure, and hydraulic means for periodically sliding the valve in its channel and hydraulically distending the walls of the chamber, said means including a cam-actuated plunger movable into a fluid-containing 15 chamber communicating with the chamber within the valve, and means for emitting oil from said chamber and replacing said oil with fresh oil.

8. A closure assembly comprising relatively 20 movable members, said assembly affording a fluid-containing chamber with a metal wall portion thereof provided by one of said members, said wall portion being capable of distending away from the opposite wall of the chamber and providing 25 an outer surface juxtaposed to a cooperating surface of the other member, and hydraulic means effective to cause the relative movement of said members in response to hydraulic pressure and to subject the fluid in said chamber to increased 30 pressure at the end of the relative movement of said members, thereby to cause outward distending movement of said wall portion and the firm sealing juxtaposition of said cooperating surfaces.

35 9. A closure assembly comprising a guide, a closure slidably movable in said guide, said closure affording a fluid-containing chamber with a metal wall portion thereof capable of buckling away from the opposite wall of the chamber, said wall portion providing an outer surface juxtaposed to a cooperating surface of the guide and normally in slidable engagement therewith, and hydraulic means effective to impose pressure upon a body of fluid to effect the movement of the closure 40 in the guide and to subject fluid in said chamber to increased pressure at the end of the movement of said closure thereby to press said wall portion into firm sealing engagement with said cooperating surfaces.

45 10. A closure assembly comprising relatively movable members, one member of which has a fluid-containing chamber with a wall portion movable substantially perpendicular to the direction of said relative movement, said wall portion 50 providing an outer surface juxtaposed to a cooperating surface of the other member, said relative movement taking place while said juxtaposition continues, means to actuate said fluid-containing member to said relative movement, said actuation means exerting its sliding force principally 55 upon portions of said fluid containing member other than said wall portion, said means also causing said perpendicular movement of said wall portion after said relative movement has been completed.

60 11. A closure assembly comprising a housing having a conduit therethrough for the transmission of fluid, a valve piece, there being a guide channel in said housing intersecting said conduit and adapted to receive slidably said valve piece, said conduit being positioned to be entered by the valve piece when in the innermost portion of the guide channel, said valve piece having a hollowed-out portion adapted to receive fluid from said channel, means to actuate said valve piece to its

innermost position and for laterally distending a portion of the valve piece adjacent said hollowed-out portion, said lateral distension taking place after said innermost position is reached, said actuating means exerting its sliding force principally upon portions of said valve other than said portions to be distended. 5

65 12. A closure assembly comprising a housing having a conduit therein, there being a channel in the housing intersecting with and extending to the opposite side of said conduit, said channel being sealed off at its end away from the conduit, a head adapted to slide in said channel, a valve-seating recess on said opposite side adapted to receive the end of said head, said channel affording parallel walls adapted to guide the head inward across said conduit into sealing relationship, the head forming with the walls of the channel a chamber for containing fluid, said head fitting at all times against said parallel walls to 20 block any appreciable movement of fluid between said conduit and said chamber, said head having at least one distensible wall whereby the head may fit more firmly within said parallel surfaces and said recess, said head having a hollow space 25 beneath said distensible wall whereby said fluid may exert a force against the distensible wall adapted to press the distensible wall more firmly against the surface of the channel means to periodically increase the amount of fluid in said 30 chamber thereby causing corresponding inward strokes of the head to its innermost and seated position with a material increase of pressure in the fluid chamber after the head has reached its innermost position thus in turn causing a distension of said distensible wall to sealing position. 35

40 13. A closure assembly comprising a housing having a conduit therein, there being a channel in the housing intersecting with and extending to the opposite side of said conduit, a head adapted to slide in said channel, a valve-seating recess on said opposite side adapted to receive the end of said head, said channel affording parallel walls adapted to guide the head inward across said conduit into sealing relationship, a piston adapted 45 to slide in the channel in its outside portion outside of said head, the head and piston forming with the parallel walls of the channel a chamber for containing fluid, said head acting at all times to block any appreciable movement of fluid between said conduit and said chamber, said head and piston being joined by linkage means permitting relative movement between the head and the piston up to predetermined limit while resisting relative movement beyond said limit, said head having at least one distensible wall whereby the head may fit more firmly within said parallel surfaces and said recess, said head having a hollow space beneath said distensible wall whereby said fluid may exert a force against the distensible wall adapted to press the distensible wall firmly against the surface of the channel means to maintain a constant amount of fluid in said chamber whereby each successive inward stroke of the piston will cause a corresponding inward stroke of the head to its innermost and seated position with a material increase of pressure in the fluid chamber after the head has reached its innermost position thus in turn causing a distension of said distensible wall to sealing position. 50

55 14. A closure assembly comprising a housing having a conduit therein, there being a channel in the housing intersecting with and extending to the opposite side of said conduit, a head adapted 60 to slide in said channel, a valve-seating recess on said opposite side adapted to receive the end of said head, said channel affording parallel walls adapted to guide the head inward across said conduit into sealing relationship, a piston adapted to slide in the channel in its outside portion outside of said head, the head and piston forming with the parallel walls of the channel a chamber for containing fluid, said head acting at all times to block any appreciable movement of fluid between said conduit and said chamber, said head and piston being joined by linkage means permitting relative movement between the head and the piston up to predetermined limit while resisting relative movement beyond said limit, said head having at least one distensible wall whereby the head may fit more firmly within said parallel surfaces and said recess, said head having a hollow space beneath said distensible wall whereby said fluid may exert a force against the distensible wall adapted to press the distensible wall firmly against the surface of the channel means to maintain a constant amount of fluid in said chamber whereby each successive inward stroke of the piston will cause a corresponding inward stroke of the head to its innermost and seated position with a material increase of pressure in the fluid chamber after the head has reached its innermost position thus in turn causing a distension of said distensible wall to sealing position. 65

70 15. A closure assembly comprising a housing having a conduit therein, there being a channel in the housing intersecting with and extending to the opposite side of said conduit, a head adapted 75 to slide in said channel, a valve-seating recess on said opposite side adapted to receive the end of said head, said channel affording parallel walls adapted to guide the head inward across said conduit into sealing relationship, a piston adapted to slide in the channel in its outside portion outside of said head, the head and piston forming with the parallel walls of the channel a chamber for containing fluid, said head acting at all times to block any appreciable movement of fluid between said conduit and said chamber, said head and piston being joined by linkage means permitting relative movement between the head and the piston up to predetermined limit while resisting relative movement beyond said limit, said head having at least one distensible wall whereby the head may fit more firmly within said parallel surfaces and said recess, said head having a hollow space beneath said distensible wall whereby said fluid may exert a force against the distensible wall adapted to press the distensible wall firmly against the surface of the channel means to maintain a constant amount of fluid in said chamber whereby each successive inward stroke of the piston will cause a corresponding inward stroke of the head to its innermost and seated position with a material increase of pressure in the fluid chamber after the head has reached its innermost position thus in turn causing a distension of said distensible wall to sealing position. 80

to slide in said channel, a valve-seating recess on said opposite side adapted to receive the end of said head, said channel affording parallel walls adapted to guide the head inward across said 5 conduit into sealing relationship, a piston adapted to slide in the channel in its outside portion outside of said head, the head and piston forming with the parallel walls of the channel for containing fluid, said head and piston being joined 10 by a link member permitting relative movement between the head and the piston up to predetermined limit while resisting relative movement beyond said limit, said head having at least one distensible wall whereby the head may fit more 15 firmly within said parallel surfaces and said recess, said head having a hollow space beneath said distensible wall whereby said fluid may exert a force against the distensible wall adapted to press the distensible wall more firmly against the 20 surface of the channel, whereby each inward stroke of the piston will cause a corresponding inward stroke of the head to its innermost and

seated position with a material increase of pressure in the fluid chamber after the head has reached its innermost position, thus in turn causing a distension of said distensible wall to sealing position, means flowably connected to said chamber to displace an extra quantity of fluid into the chamber, means to operate the piston and said displacement means in chronological relationship so that said extra fluid is displaced into the chamber during the end part of the 10 inward stroke of the head.

15. A slide valve assembly comprising a hollow fluid-containing valve, a guide structure in which said valve is movable, said structure providing a guide extending into and interfitting with the open end of said hollow valve, said guide affording sealing surfaces cooperating with the inside surfaces of said valve, and means for actuating said valve to slide the same along a path defined by said structure and for distending the valve at the 20 end of its path.
